Primary Examiner — Amy C Wierenga(57) **CLAIM**

I claim the ornamental design for an offset grid strainer hub, as shown and described.

DESCRIPTION

This is a Continuation-in-Part of application Ser. No. 29/534,754 filed on Jul. 30, 2015.

FIG. 1 is a perspective view showing my design of the offset grid strainer hub;

FIG. 2 is a right-side view thereof;

FIG. 3 is a left view thereof;

FIG. 4 is a top internal view thereof; and,

FIG. 5 is a bottom view thereof.
